UNITED STATES PATENT OFFICE.

HEINRICH FREISE, OF HAMME, NEAR BOCHUM, GERMANY.

COVER-LOCKING DEVICE FOR DUST-BINS.

No. 825,963.

Specification of Letters Patent.

Patented July 17, 1906.

Application filed July 6, 1905. Serial No. 268,579.

To all whom it may concern:

Be it known that I, HEINRICH FREISE, a subject of the German Emperor, and a resident of 213 Dorstenerstrasse, Hammie, near Bochum, Germany, have invented certain new and useful Improvements in Cover-Locking Devices for Dust-Bins and the Like, of which the following is a specification.

The present invention relates to a cover-locking device for dust-bins and the like.

The locking device according to the present invention is intended to keep the dust-bin or the like closed until the same is inserted sufficiently far into the admission-opening of a dust-wagon suitable for the dust-bin in question in order to prevent its contents from being spilled. According to the present invention this object is attained by a bow-shaped piece or the like arranged revolubly on the dust-bin engaging by means of its hook-shaped bend in such a way with projections, elevations, or the like arranged on the cover or lid of the bin that the said bow-shaped piece is not slipped off downward until after the dust-bin has been inserted sufficiently far into the admission-opening of the dust-wagon, after which the cover or lid of the bin is released.

In the accompanying drawings several embodiments of the subject-matter of the invention are illustrated.

Figure 1 is a side elevation of the dust-bin; Fig. 2, a plan of the same; Figs. 3 and 4, a side elevation and plan, respectively, of another form of the dust-bin; Fig. 5, a plan of a third form of dust-bin, Fig. 6 illustrating the manner in which the cover of the dust-bin is released when the dust-bin is inserted in the frame-opening of the dust-wagon, and Figs. 7 and 8 showing in vertical cross-section parts of two different dust-wagons with which, by way of example, the dust-bin can be used.

The dust-bin *a* is provided with a cover or lid *c*, revoluble about a hinge *b*. At the front of the cover *c* a torus-roll *d* or the like or another projection or elevation is arranged. The eyes *e* of the dust-bin *a*, which also may serve for receiving a carrying-handle *f*, carry a bow-shaped piece *g* or the like. The latter possesses a hook-shaped bend *h*, which is pressed from below upward resiliently over the roll *d* of the cover *c*. Thereupon the ends of the bow, and with them the eyes *e* and the adjacent side parts of the dust-bin, move resiliently inward. Consequently

the bow *g* lies firmly on the cover *c*, and consequently secures the latter in its closed position. If the dust-bin *a* is raised or tilted, it remains nevertheless usually closed in a dust-tight manner. Not until after the insertion of the dust-bin *a* in the opening *i* of the frame *k*, Figs. 6 and 7, or the lowering of the same into the admission-opening *o* in the wagon-cover *s*, Fig. 8, does the cover-locking device come out of action. The bow *g* at a suitable place—for example, at *l*—is so shaped and brought into such a position with regard to the dust-bin *a* that when it arrives just in the frame-opening *i* it strikes against the frame *k*. (See the left of Fig. 7.) On inserting the dust-holder still farther the bow *g* is pressed back downward (compare Fig. 6) by means of the side parts of the frame *k*, whereupon the closing-flap *n* is raised slightly. When the bow *g* has been slipped off and the cover *c* has thereby been released, the dust-bin is tilted and discharged. (See the right of Fig. 7.) In the case of the wagon, a portion of which is illustrated in Fig. 8, the release of the cover *c* does not take place until after the tilting of the dust-bin *a* and the pressing backward of the closing-flap *r*, arranged on the lever *q*, said release being effected by the part *l* of the bow *g* striking on the edge *p* of the admission-opening *o* during the lowering of the dust-bin *a* into the admission-opening *o*, which has become free after the flap *r* has been pressed back. The bow *g* is thereby driven back, while the bin is being further lowered. The above-described dust-bin can also be employed with other suitable dust-wagons or the like.

According to Figs. 1 and 2 the torus-roll or another elevation is arranged on the cover *c*. Figs. 3 and 4 show a form in which the elevation *d'* is extended in front of the cover *c*. The bow *g* is shaped in correspondence with the device. Fig. 5 illustrates the construction of the bow *g* when the same engages with parts *m*, which project laterally over the cover *c*.

What I claim as my invention, and desire to secure by Letters Patent of the United States, is—

1. A cover-locking device for dust-bins consisting of the combination with the bin of a hinged cover *c*, a substantially bow-shaped piece *g* revolubly mounted on said bin, said piece having a hook-shaped bend adapted to engage with said cover in its closed position

and lateral portions *l* adapted to engage with the sides of the admission-opening in the dust-wagon when the bin is inserted in said opening for the purpose of releasing the cover and enabling the contents of the bin to be discharged, substantially as described.

2. A cover-locking device for dust-bins consisting of the combination with the bin of a hinged cover *c* provided with a projection, 5 a substantially bow-shaped piece *g* revolubly mounted on said bin, said piece having a hook-shaped bend adapted to engage with said projection on said cover in its closed position and lateral portions *l* adapted to engage with the sides of the admission-opening in the dust-wagon when the bin is inserted in said opening for the purpose of releasing the cover and enabling the contents of the bin to be discharged, substantially as described.
- 10 3. A cover-locking device for dust-bins consisting of the combination with the bin of 15
- 15
- 20
- 25
- 30
- 35

a hinged cover *c* provided with a projection having substantially the shape of a torus-roll, a substantially bow-shaped piece *g* revolubly mounted on said bin, said piece having a hook-shaped bend adapted to engage with said roll-shaped projection on said cover in its closed position, and lateral portions *l* adapted to engage with the sides of the admission-opening in the dust-wagon when the bin is inserted in said opening for the purpose of releasing the cover and enabling the contents of the bin to be discharged, substantially as described.

In testimony whereof I have signed my name to this specification in the presence of two subscribing witnesses.

HEINRICH FREISE.
